MATCH BOOK MACHINE

Samuel E. Rahe, Springfield Gardens, N. Y., assignor to Berst-Forster-Dixfield Co., New York, N. Y., a corporation of Maine

Application March 16, 1938, Serial No. 196,169

2 Claims. (Cl. 93—2)

This invention relates to improvements in match book machines, and particularly to such machines or portions thereof by which match cards are introduced into the enclosing cover therefor.

5 *Objects*

The objects of the invention are to generally improve machines of the character indicated to produce a machine which will make match books more rapidly; to speed up production without increase of floor space for machinery; to make match books more economically and better than by present practice; to provide improved means for carrying formed cards; to improve the discharging mechanism for the cards from the carrying means; to utilize the discharge of the cards to effect partial folding of the cover; to obtain precision of action and placement of the cards with respect to the cover; to maintain the precision of placement as long as required in the machine until the cover and cards are stapled or otherwise permanently secured; to enable use of rugged and lasting operating parts; to secure simplicity of construction and operation; and to obtain other advantages and results as may be brought out in the following description.

20 *Drawing*

30 Referring to the accompanying drawing in which like numerals of reference indicate similar parts throughout the several views:

Figure 1 is a vertical sectional view looking down from the side of a machine embodying the features of the present invention;

35 Figure 2 is a plan of a portion of one bank of match cards and their supports and associated ejecting means;

Figure 3 is a perspective view of one of the card supports;

40 Figure 4 is a vertical sectional view of one of the card supports showing cards carried thereby;

Figure 5 is a rear view of the said support;

Figure 6 is a horizontal plan with a portion of the upper clip broken away;

45 Figure 7 is a perspective view of the completed match book; and

Figure 8 is an upper edge view of a certain spring for engaging the holder frictionally upon its supporting bar.

50 *Description*

In the specific embodiment of the invention illustrated in said drawing, it will be understood by those familiar with the art that match books or packets of the general type illustrated in Fig-

ure 7 have been available on the market for many years. The invention herein set forth is directed largely to the assembling of the cards of matches in the covers ready to be stapled. Inasmuch as machines now exist and are well known for preparing the cards, such as the individual units 10 here shown and slitting the same as at 11 for providing a plurality of match stems 12 side by side, the inner ends of which remain integral with the base 13 of the card and the outer ends of which are spread and dipped in ignitable material to provide the tips 14, further illustration of such machines is deemed unnecessary. Suffice it to say, that the present invention is a part of that machine in so far as the card or unit receiving and holding means also receives and holds the cards during any of the operations described prior to the assembly operation with which the present disclosure is more particularly concerned.

As here shown, I provide a plurality of holders 15 which are advanced continuously or intermittently from the part of the machine performing the mentioned preliminary operation to the part of the machine where assembling is effected. These holders may conveniently be part of or carried by continuous chains or belts, and in the present disclosure are illustrated as arranged in horizontal banks or series in Fig. 2 and the several horizontal series arranged to move simultaneously in a direction transverse to the series, that is, vertically. In Fig. 1 there is shown one holder of each of several of the horizontal series, so that it will be understood that the holders shown in Fig. 1, are moving vertically downward in operation and that each holder shown is representative of a horizontal bank of holders at the level indicated. It is to be understood however, that while I refer to horizontal banks of holders and a vertical series of these horizontal banks, in order to assist in the more ready understanding of the particular disclosure, it is not to be understood that I limit myself to a machine wherein the banks of holders must necessarily be horizontal or the forward feeding of the several banks of holders will be in a vertical direction.

Said holders 15 are preferably all of identical construction and description of one will therefore serve the purpose to describe all. Each 50 holder, of which one is illustrated alone in Fig. 3, preferably comprises a body portion 16 from the rear of which projects a stud 17 for engagement with cams (not shown) in another part of the machine. The holders are moved downward- 55

ly in groups or banks, say of ten, in a row, by belts or chains 18, the construction of which are of course co-related to the construction of horizontal holder carrying bars 26 (hereafter more fully described) so as to obtain the desired travel of the holder with the belt or chain, and feed the holder through the machine in proper position at all times. From the opposite side of the holder from said stud 17 the holder projects outwardly 10 to provide a fixed jaw 19, and the construction is preferably such that there is a horizontally fixed jaw 19 at the top of the holder in use and a similar fixed jaw 19 at the bottom of the holder, these jaws being parallel to each other and substantially the width of the card or unit 10 which is to be gripped. Furthermore, the depth of the said jaws 19, 19 is preferably made to correspond substantially to the depth of the base portion 13 of the card or unit 10. It is intended that 15 each holder shall receive two cards or units, one flatwise of the lower fixed jaw at the bottom of the holder and another at the upper fixed jaw at the top of the holder with both units projecting in parallel relation to each other with the tips 14 of the match stems away from the holder.

In order to grip the units 10, a spring jaw 20 is provided below the lower jaw and another like spring jaw 20 is provided above the top fixed jaw 19. The construction of each of these spring jaws is such that an inner portion 21 thereof is in flatwise engagement with the top portion 16 of the holder and rigidly secured therat by rivets 22 or other suitable means. Said portion 21 of the spring jaw extends crosswise of the holder 25 but at a distance from each edge of the holder is offset, as at 23, to provide a channel 24 between the fixed jaw and the spring jaw next the side edges thereof. The spring jaw extends at both sides in a direction away from the chain 30 or stud 17 and the side portions of the spring 40 or jaws curl upward and are connected by a cross-piece 25 at the front part of the holder thereby enabling the match card or unit 10 to be slid between the fixed jaw and spring jaw and be gripped by virtue of the resiliency of the spring 45 jaw. The forward edge of the fixed crosspiece 21 and the forward edge of the offset portion 23 will constitute a stop to limit and position the card upon insertion between the jaws. It is to be observed that the spring jaws 20 have card-engaging portions only next the sides of the 50 holders, so the mid-portions of the match cards are not frictionally held. Ultimate ejection of the card from the holder is by a push effective on the card at its portion only in the rear of where the spring jaws are pressing, and therefore introduces no likelihood of splitting the card.

Referring now to Figs. 1, 2 and 4, it will be noted that said holders 15 are channeled horizontally hollow and are slidably positioned upon horizontal bars 26, each bar supporting the horizontal bank or series of holders. In order to mount the holders in proper position upon the bars, leaf springs 27 are inserted in the holders, 60 the tips 28 of the springs being bent as shown in Fig. 8 to prevent longitudinal displacement thereof from the holders. The midportion of the spring bears resiliently against the bar 26 and obtains ample frictional engagement between the bars and holders to retain the said 65 holders in precise position to which they are slid in operation upon the bars.

Referring particularly to Figs. 1 and 2, it will be observed that I provide a horizontally disposed 70 ejector 29 having forwardly projecting blades 30

of proper width to enter the pair of adjacent openings or channels 24 of two adjacent holders. As the ejector moves in the direction indicated by the arrow in Fig. 2, the forward edges of the blades 30 entering said openings 24 engage the inner edge of the base portion 13 of the several units next the opposite ends of each unit and for as much of the width of the unit as the width of frictional holding by the side or offset portion 23 of the spring jaw 20. Continued forward movement of the ejector therefore will apply even pressure next both ends of the units and will force the units out of the several holders and cause them to fall upon a horizontal ledge or shelf 31. The machine is preferably constructed so as to first eject the card held by a lower jaw of a holder upon the shelf, and let the card remain upon the shelf until the second card carried by the upper jaw of the same holder is ejected to then rest upon the first card. A stop plate 32 is shown above the shelf at a proper distance forward from the holder to position the dipped ends of the match cards at the desired position upon the shelf, this structure also including a curved overlying guide plate 33 carried by a suitable support 34 in front of the guide plate 33 to make it more certain that the cards on the ledge or shelf 31 will be properly arranged or stacked one upon the other with the match tips in juxtaposition. When two sets of cards have been ejected as described, the stop plate 32 is moved upward out of the path of the cards to permit their further forward movement through the machine and to the means for covering and packing them. This movement is effected by a suitable arm 35 which freely engages the plate 32 and is attached to a rock shaft 36, the latter having a crank arm 37 suitably actuated in timed relationship to the movement of holder and other parts and not further illustrated in detail because it is so obvious to a mechanic.

Disposed in front of the matches or cards on shelf 31, and at the opposite side thereof from stop plate 32 from the match cards, and perpendicular to the horizontal disposition of the shelf, is a chute having a portion 38 thereon above the shelf and a lower portion 39 aligned with the upper portion and situated below the shelf. This chute receives by gravity or otherwise a flat cover blank 43. A new blank is dropped or fed into the chute for each pair of match cards as fast as assembly of one pair of match cards and its cover blank is effected. The assembly is obtained by lever 42 lifting stop plate 32 after the match cards are on the shelf, and by a finger 41 on a lever 42 sliding the match cards forwardly toward the cover blank 43. It will be observed that the shelf 31 is slotted as at 43 from its edge next the holders toward its edge 45 next the chute, and finger 41 is normally retracted to a position toward the holders so that the match cards fall upon the shelf in front of finger 41. Lever 42 is under actuation of suitably timed mechanisms to move toward the chute 50 immediately upon stop plate 32 lifting, and thus the pair of match cards will be slid forwardly together at the proper time, after which the lever 42 and finger 41 retract to position shown in Fig. 1 ready for another pair of match cards. 55 It is further to be understood, that there are as many chutes, levers, fingers, and slots for the fingers as there are holders in a horizontal bank. The fingers 41 are preferably centrally disposed with respect to the respective match 60

cards and holders between the side edges thereof so as to propel the match cards without any tendency of the cards deviating from straight line forward movement.

5 It is now to be observed that as match cards 18 are slid forwardly by finger 41, that they engage at their tip ends against a midportion of the cover blank 40, and the pressure exerted by the finger 41 will suffice to bend the blank 10 where engaged by the match tips and thus disposes top and bottom portions of the blank across the pair of match cards to constitute the top and bottom of the final cover. The ultimate bending of the lower end margin 44 as shown 15 done in Fig. 7, is accomplished at a later time and by mechanism not here shown. Likewise, the application of a staple 45 through the bent over end margin 44, the base end 13 of the match cards and the lower or back portion of 20 the cover 40 is likewise later accomplished by other means not here shown.

When the match cards 18 are pushed forward against covers 40 as described, the partially formed covers and the several groups or units 25 of cards are pushed between and grasped by gripping jaws 46 and 47 which may conveniently be part of a conveyor 48 which moves transversely of the feed up to this point. That is, the movement of the partly made books in after 30 engagement by jaws 46, 47 of this second conveyor 48 is transverse to the travel of the holders 15 or dipping carriers 18 at this point. The movable jaw 47 of each gripper is pivoted at 49 to the fixed jaw, and the jaws are normally 35 closed by a spring 50 interposed at the far side of the jaws between the same. The pairs of jaws have the same spacing on the conveyor 48 as the spacing of the holders 15 on their bars 25. The conveyor must have an intermittent movement, being at rest when lever 42 and finger 41 40 force the assembled cards and covers between the jaws, after which the conveyor moves on to present a new group of jaws opposite the several holders 15 of the next bank as that bank discharges its cards upon shelf 31.

Briefly reviewing the operation and with particular attention to Fig. 1, it will be understood 50 that individually formed units or cards of prepared matches arrive at the part of the machine involved in the present invention already positioned in holders 15, there being two cards in each holder but each card being held by a distinct gripping means, one at the bottom of the holder and the other at the top of the holder. 55 The holders move downward at regular intervals and as each card comes to a position somewhat above shelf 31, ejector 29 moves forward with the several blades 30 thereof entering the channels or openings 24 of two adjacent holders, thereby forcing all of the cards of one bank of 60 holders simultaneously onto shelf 31 in the precise spacing thereof as determined by the spacing of holders 15 on the bar 25 for that particular bank. The ejector 29 thereupon retracts 65 and the cards carried at the upper part of the same holder move down into the plane of the ejector which again moves forward and ejects a second set of cards in like manner, causing them to fall in juxtaposition upon the first set of cards 70 on the shelf. Ejector 29 then retracts ready to similarly eject the next set of cards from the next holder when it comes into proper position. In the meantime, however, a cover 40 has dropped down chute 38, 39 resting upon a stop

51, and blade 32 at the tip end of the matches which has assisted in accurately positioning the match cards, rises and as the cards move forward they engage the midportion of said cover, bending the cover around the match tips, thus being forced with the match cards between jaws 46, 47. The accurate placement of the cards upon the shelf and the necessarily accurate placement of the cover in its chute results in the accurate assembly of the cards within the cover, it being usual practice for the cover, to be slightly wider than the match cards. The construction and operation is one which enables the cards to be centrally disposed between the side edges of the cover and in such position they are forced together into the receiving jaws which retain the parts in the precise relationship indicated while further bending and stapling is effected in other parts of the machine not here shown. All of the moving parts of the machine are inter-related by gears, chains or otherwise so as to maintain a precision of operation and timing, as will be understood by persons skilled in the art. This timing of the movement of the several parts includes the intermittent travel of conveyor 48 carrying jaws 46, 47 by which these jaws are moved along in groups say of ten at a time, to correspond to the similar grouping of ten holders for each bank of holders. In other words, the holders may be arranged in banks of ten, the cover chutes likewise in banks of ten, the advancing fingers 41 in banks of ten thereby assembling ten pairs of cards and their respective ten covers at one time and inserting all ten simultaneously between ten pairs of jaws. Then, as the next 30 bank of holders advances to discharge its cards upon the shelf the receiving conveyor 48 moves along to present ten more unoccupied pairs of jaws in position to receive the next group of cards and covers. I do not confine the invention, however, to assembling ten books at a time, as the machine may be constructed or employed for assembling more or less than that number at one time.

I claim:

1. In a match book machine, a holder for match cards comprising a body portion having a yieldable member at one face thereof, said yieldable member forming means at opposite edges of the body portion for gripping the match card at its edges and with the gripping means out of contact from the match card intermediate said edges, said gripping means being rearwardly open for receiving an extruding means for the match card at the part of the card which is gripped whereby the card may be extruded by a direct push at the part thereof which is gripped and thereby avoid breaking the card while being extruded from the holder.

2. In a match book machine, a holder for match cards comprising a body portion having yieldable members at opposite faces thereof, each said yieldable member forming means at opposite edges of the body portion for gripping the match card at its edges and with the gripping means out of contact from the match card intermediate said edges, each said gripping means being rearwardly open for receiving an extruding means for the match card at the part of the card which is gripped whereby the card may be extruded by a direct push at the part thereof which is gripped and thereby avoid breaking the card while being extruded from the holder.

SAMUEL E. RAHE.
